(57) **CLAIM**

The ornamental design for a portable pet supply case, as shown and described.

DESCRIPTION

FIG. 1 is a perspective view of the portable pet supply case; FIG. 2 is a front elevation view of the portable pet supply case;

FIG. 3 is a left side elevation view of the portable pet supply case;

FIG. 4 is a back elevation view of the portable pet supply case;

FIG. 5 is a right side elevation view of the portable pet supply case;

FIG. 6 is a top plan view of the portable pet supply case; and,

FIG. 7 is a bottom plan view of the portable pet supply case. The broken lines shown in the drawings are for the purpose of illustrating portions of the article that form no part of the claimed design.
